NAIL-DRIVING MACHINE

Clinton J. Bacon, Los Angeles, and Samuel J. Kent, Van Nuys, Calif., assignors to Nu-Matic Nailer, Inc., Los Angeles, Calif., a corporation of California

Application August 1, 1955, Serial No. 525,745

6 Claims. (Cl. 1—44.4)

This invention relates to improvements in nail-driving machines and deals more particularly with machines that feed nails automatically into position to be driven by pneumatic or percussive means.

Because of their percussive nature, metal fatigue, resulting in the fracture of parts subject to percussion, is a frequent problem. Such failure most frequently affects nail driver-retaining means used in the construction, since this means has the percussive force on the driver transmitted to it. Reference is made to Patents Nos. 2,546,354, dated March 27, 1951; 2,652,564, dated September 22, 1953; and 2,679,044, dated May 25, 1954, as showing driver-retaining means that are sources of such failure.

Accordingly, an object of the present invention is to provide a machine of the character indicated in which the percussive forces by the nail driver on the retainer provided for said driver are effectively absorbed to minimize metal fatigue in the parts with a resultant decrease in failure of the parts.

Another problem in such machines is the proper feed of nails, as from a hopper, to a position from which they are driven into a board. Machines of the type shown in said patents use a tiltable hopper in which the nails are agitated to cause their feed along a slideway to an escapement means that releases said nails, one by one, as the machine is operated. Since the hopper is movable and the mentioned slide has a fixed position, nail jamming frequently occurs at the point where the nails leave the hopper.

In order to correct this condition, it is another object of the invention to provide improved means effecting such interconnection of the nail hopper and the feed slide of a nailing machine so that proper and non-jamming feed of nails may be carried out.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes, one embodiment of the present invention, which is given by way of illustration or example only.

In the drawings, like reference characters designate similar parts in the several views.

Fig. 1 is a side elevational view of a nail-driving machine according to the present invention and shown in nail-driving position.

Fig. 2 is a similar but fragmentary view showing the machine in extended position preparatory to driving a nail.

Fig. 3 is a front elevational view, with the upper part broken away, showing said machine in the position of Fig. 1.

Fig. 4 is an enlarged and fragmentary vertical sectional

2

view showing the nail-feeding and nail-driving details of the machine.

Fig. 5 is a plan view of the portion of the machine that is shown in Fig. 4.

5 The machine that is illustrated comprises, generally, a nose piece 10 fitted with a stirrup 11 by means of which the foot of an operator may hold said nose piece in nail-driving position, a rigid outer guide frame 12 affixed to the nose piece and extending vertically upward, air-actuated hammer means 13, a slide frame 14 connected to the means 13 and guided by the frame 12, a nail driver 15 guided in the nose piece and in operative engagement with the hammer means 13, resiliently-mounted retainer means 16 for the nail driver and carried by the slide frame 14, nail hopper means 17 connected to and movable by the slide frame 14, nail-guiding and -feeding means 18 affixed to the nose piece, and means 19 extending between the means 18 and the hopper means 17 to guide nails from the latter to the former.

10 The nose piece 10 and the stirrup 11 are connected by a universal ball joint 20 that enables a change of angular disposition of the machine with relation to the stirrup. Said nose piece is provided with an axial through passage 21 and with a lateral slot 22, the former to receive a nail 23 to be driven and the latter to pass such a nail to the former. Said slot is shown with a widened upper portion 24 to pass the head 25 of such a nail. As best seen in Fig. 3, the nose piece 10 is transversely 15 widened to be substantially wider than the diametral size of the lower end 26. The guide frame 12 is affixed to said widened upper portion of the nose piece.

20 The guide frame 12 is shown as comprising a pair of vertically disposed side members 27 that constitute guides, 25 the same being secured to the opposite sides of the nose piece and, therefore, are disposed on either side of the axis of passage 21.

25 At its upper end the frame 12 is provided with a cross bar 28 offset rearwardly from members 27 and connected thereto by members 29. While shown as fabricated of separate members, it will be understood that the guide frame 12 may be integrally formed as a casting or forging.

30 The hammer means 13 is generally conventional of 30 pneumatic percussive devices. As shown, the same comprises a cylinder 30 that has an upper tubular extension 31 which terminates in a handle 32 that has an air connection 33 and is provided with a control valve exemplified by valve handle 34. Said cylinder 30 is provided with an axial bore in which a piston 35 is guided, the latter being reciprocatively movable by compressed air supplied through connection 33. The particular form 35 of the pneumatic hammer means 13 is not pertinent to this invention, it only being necessary to provide a percussive hammer or piston 35. An axial guide 36 is preferably provided in the lower end of cylinder 30, the same holding the upper end of the driver 15 in alignment with the piston 35, as best shown in Fig. 4.

35 The slide frame 14 comprises vertically spaced members 37 and 38 that are connected by a longitudinal member 39. The cylinder 30 is mounted in members 37 and 38 and the latter are provided with guide notches 40 in which the guide members 27 are slidably fitted. Thus, the hammer means 13 is vertically reciprocable relative 45 to the nose piece 10.

40 The nail driver 15 comprises an elongated element having a pilot end 41 guided in the guide 36 of the pneumatic cylinder 30, said end being in percussive engagement with the reciprocative piston 35. The opposite end of said driver comprises a shank 42 that is slidably fitted in axial bore 21 of the nose piece and, between said pilot end and

shank, the driver is provided with an enlargement 43 that has a position between the lower end of the pneumatic cylinder and the upper end of the nose piece. The lower end of said enlargement constitutes an annular shoulder or abutment 44.

The retainer means 16 is shown as a slide member 45 that spans between and has sliding engagement with the frame guide members 27. A hole 46 in said member 45 passes the driver shank 42 and the top face thereof has abutting engagement with shoulder 44, as shown in Figs. 2 and 3. A pair of studs 47 is affixed to member 45 on either side of hole 46, said studs extending through clearance holes 48 in slide member 38 and terminating in heads 49. Compression springs 50 around said studs have end abutment with members 38 and 45 and compensating springs 51 around said studs have end abutment with heads 49 and member 38.

It will be seen that slide member 45 is resiliently mounted on springs 51 and that springs 50 allow resilient movement of member 45 toward and from member 38. It is this member that retains the pilot end 41 of the driver 15 within the guide 36 and in operative engagement with the piston 35, when the machine is extended, by the engagement of said member with the shoulder 44, as shown in Figs. 2 and 4.

The nose piece 10 is provided with a compressible buffer member 52 against which the slide or retainer member 45 abuts, the latter being cushioned by the buffer member 52.

When the machine is extended, as in Fig. 2, a nail 23 assumes a position in passage 21 below the lower end of driver shank 42. The operator depresses the hammer means 13 which is guided by frame 12 to, first, bring said shank into engagement with the head of said nail, and to thereafter unseat the driver enlargement 43 from member 45 and force the same in a direction to further intrude the driver pilot 41 into cylinder 30. See Fig. 4. Since the downward movement of the means 13 is thus arrested, it becomes necessary, in order to drive the nail, to set the piston 35 into reciprocative movement so as to percuss against the nail driver which transmits such percussive force to the nail.

As the nail is driven, the means 13 follows downwardly until the slide member 45 encounters buffer or cushion 52 which arrests the downward movement of said member. See Fig. 4. Since the driving movement of the means 13 continues, the slide frame 14 moves down against the resilient resistance of springs 50 until the nail is driven home, at which time the shoulder 44 will again abut the member 45 and the downward movement of the hammer necessarily stops. The operator then lifts the machine back into its extended position.

It will be noted that the percussive forces on the driver are positively transmitted to the nail but only resiliently affect the retainer means 16 by reason of the springs 50 and 51 and the buffer or cushion 52.

The nail hopper means 17 is shown as comprising a pair of arms 55 that are pivotally connected at one end to the slide frame 14 at 55a, and at the opposite end to links 56 at 56a. The links 56 are pivotally connected to the bottom of a hopper or container 57. Intermediate the ends of said arms 55, the same are pivotally connected to struts 58 at 58a and the struts 58 are pivotally connected, at 59, to fixed rearward extensions 60 of the nose piece. Said extensions 60, at the ends thereof spaced from pivots 59, have pivots 61 for brackets 62 secured to the bottom of hopper 57 forward of where links 56 are connected. The extensions are rendered rigid by braces 63 that connect them to the guide frame 12.

It will be obvious that the downward pressure on the handle will depress the hammer means 13 from its extended position, as shown in Fig. 2, and thereby oscillate the arms 55 about the center pivots 58a. These pivots serve as fulcrums for the arms 55, so that when reciprocating

ing movement of the means 13 imparts oscillating movement to the arms, through the pivoted connection 55a, the hopper 57 will be tilted upwardly and downwardly, depending upon the direction of reciprocation of said means 13, by means of the links 56 interconnecting the hopper and the arms 55 at the pivots 56a. Thus the nails in said hopper are agitated during operation of the machine.

This agitation is used to cause nails, point first, to pass along a longitudinal slot 64 in the bottom of the hopper and to fall therefrom when the hopper is tilted front end downward, as in Figs. 1 and 4, as will be explained below.

The means 18 comprises sloping nail-guiding members 65 that define a slot 66 therebetween, said slot being longitudinally aligned with the slot 64. At its lower end, said means includes an escapement 67 that is connected by means 68 to be operated by movement of arms 55. Each time the driver is operating to sink a nail, the escapement is operated so that same will release another nail to the position shown in Fig. 4 at the right of the driver, preparatory to moving into the passage 21 upon upward retraction of the driver. Said means, per se, forms no part of the present improvements and here constitutes the means that mounts the means 19.

The means 19 is shown as comprising curved extensions 69 of the guide members 65, the curvature of said extensions being generated around the axis of pivots 61 and in tangent relationship with the bottom wall of the hopper and in which slot 64 is provided. Consequently, said bottom wall retains tangency with said extensions in all positions of tilt of the hopper, as clearly shown by the drawings.

The means 19 further comprises a pair of flat spring members 70 that are superposed on members 65 and similarly spaced to provide slot 66. Said spring members are secured to guide members 65, as by plates 71, and extend rearward (Fig. 1) between plates 72, affixed to the bottom of the hopper and disposed on either side of slot 64, and retention washers 73 that slidably clamp the springs against plates 72.

Since plates 71 affix one end of the springs to the feed means 18 and inasmuch as the hopper tilts back and forth on the axis of the pivots 61, there is a sliding engagement between the plates 72 at the bottom of the hopper and the free ends of the spring members 70, the latter flexing over the curved extensions 69 accordingly. Thus, regardless of the angle of tilt of the hopper, any nails therein extend pendent through the slot 64 thereof also extend between spring members 70. Accordingly, the nails cannot become accidentally jammed, because said members 70 constitute a continuous means for guiding nails to the escapement 67.

While the foregoing has illustrated and described what is now contemplated to be the best mode of carrying out our invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described our invention, what we claim and desire to secure by Letters Patent is:

1. A nail-driving machine comprising a nose piece having a through passage adapted to house a nail to be driven, a pneumatic device aligned with the nose piece and having an air-reciprocated element, an outer guide frame affixed to and extending upwardly from the nose piece, a slide connected to said device and engaged with the guide for reciprocatively guiding the device longitudinally relative to the nose piece, a nail driver having a shank at one end extending into the passage in the nose piece and having an opposite end in percussive engagement with the reciprocative element of the pneu-

matic device, and resiliently-mounted driver-retaining means carried by said slide for holding the driver in operative engagement with said reciprocalative element before the shank of said driver encounters a nail in the passage of the nose piece.

2. A nail-driving machine comprising a nose piece having a through passage adapted to house a nail to be driven, a pneumatic device aligned with the nose piece and having an air-reciprocated element, an outer guide frame affixed to and extending upwardly from the nose piece, a slide connected to said device and engaged with the guide for reciprocatively guiding the device longitudinally relative to the nose piece, a nail driver having a shank at one end extending into the passage in the nose piece and having an opposite end in percussive engagement with the reciprocalative element of the pneumatic device, resiliently-mounted driver-retaining means carried by said slide for holding the driver in operative engagement with said reciprocalative element before the shank of said driver encounters a nail in the passage of the nose piece, and a compressible cushion interposed between the nose piece and the guide-retaining means to absorb the percussive forces transmitted by the driver to said retaining means.

3. A nail-driving machine according to claim 1: said driver-retaining means comprising a member in independent sliding engagement with the guide frame, and spring means between said slide and said member compressible upon contact between said member and the nose piece.

4. A nail-driving machine according to claim 1: said driver-retaining means comprising a member in independent sliding engagement with the guide frame, and spring means between said slide and said member com-

pressible upon contact between said member and the nose piece, a compressible cushion being interposed between the nose piece and the mentioned member to absorb percussive forces on the member.

5. In a percussion machine of the character referred to having a cylinder in which an air-reciprocated element is disposed, the combination comprising a driver member aligned with and in percussive engagement with the mentioned element, a member engaged with the driver member to hold the latter in percussive engagement with said element, and resilient means interconnecting said cylinder and second-mentioned member to absorb percussive shocks imparted by the air-reciprocated element through the driver to said second member.

10 15 6. In a percussion machine according to claim 5: a guide means for said cylinder whereby the latter is movable in the direction of the percussive forces, and second guide means for said second member.

7. In a percussion machine according to claim 5: a nose piece in which said driver member operatively moves, a guide carried by the nose piece, and means slidably interconnecting the cylinder and said guide.

20 25 8. In a percussion machine according to claim 7: said second member having slide-guiding engagement with the mentioned guide.
